His Attorney.

UNITED STATES PATENT OFFICE

DAVID C. PRINCE, OF SCHENECTADY, NEW YORK, ASSIGNOR TO GENERAL ELECTRIC COMPANY, A CORPORATION OF NEW YORK

VAPOR ELECTRIC DEVICE

Application filed February 16, 1927. Serial No. 168,811.

My invention relates to vapor electric devices, such as a rectifier provided with a mercury cathode and a plurality of anodes, and has for its principal object the provision of an improved arrangement of parts and method of operation whereby cooling of the device is facilitated and the formation of destructive arcs is avoided.

One of the most serious difficulties encountered in the operation of mercury arc rectifiers is the formation of destructive arcs either between different anodes or between a negatively charged anode and the cathode. Such arcs may be caused by pockets of comparatively high vapor pressure produced in the region of an anode either by volatilization of the anode material or by the volatilization of mercury which is condensed in the upper part of the tank and drops or runs down on the hot surfaces of the anodes. In order to avoid destructive arcs, which are commonly designated by the term "arc-back", it is, therefore, desirable that a low vapor pressure be maintained in the active region around the anodes. It is also desirable that the vapor pressure in the condensing or inactive region of the device be maintained at a comparatively high value for the reason that the efficiency of the cooling system is dependent on the existence of a high temperature and pressure in this region.

In accordance with my invention, arc-back is prevented and cooling of the device is facilitated by an improved arrangement of parts whereby the vapors emanating from the cathode are maintained at a comparatively low pressure and high velocity in the region where they are separated from the arc stream and are maintained at a comparatively high pressure and low velocity in the region where they are condensed.

My invention will be better understood from the following description when considered in connection with the accompanying drawing and its scope will be pointed out in the appended claims.

The drawing is a cross-sectional view of a mercury arc rectifier constructed in accordance with my invention.

50 This rectifier comprises an evacuated re-

ceptacle 1 which encloses a mercury cathode 2 and a plurality of anodes 3 each electrically insulated from the receptacle 1 by an insulation sleeve 4 and provided with an external terminal 5. The cathode 2 is insulated from the tank 1 by an insulation receptacle 6 and is connected to an external terminal 7 through a lead 8 which is surrounded by an insulation sleeve 9 and is electrically insulated from the tank 1 by an insulation sleeve 10. Means comprising a casing 11 are provided for circulating a cooling medium in contact with the exterior of the tank 1. It will be observed that the tank 1 is provided with an inner flange portion 12 which extends inwardly over the edge of the insulation vessel 6; that a contracting nozzle 13 is arranged above the cathode 2 to receive the vapors which are projected upwardly therefrom; and that suitable openings 14 are provided for permitting the return of the condensed vapor to the insulation receptacle 6.

When a vapor flows through a contracting nozzle from a vessel at high pressure into one at low pressure, the maximum velocity of egress is obtained with a drop of approximately 50% in pressure. Thus if the vapor in the cathode chamber below the nozzle 12 is assumed to be discharged through the nozzle 12, this vapor reaches the lowest pressure and highest velocity in the region between the nozzles 12 and 13 where it is separated from the arc stream which goes to the anodes. It is then delivered to the large end of the nozzle 13 at a high velocity, is decelerated until it reaches the narrowest part of the nozzle 13, is further decelerated in the upper part of the nozzle 13, and comes substantially to rest in the condensing chamber at a pressure which is substantially double that in the region between the nozzles.

In view of the foregoing explanation it will be apparent that this method of operation involves the steps of accelerating the vapor up to the nozzle 12, expanding the vapor to its highest velocity and lowest pressure in the region where it is separated from the arc stream, decelerating the vapor up to the contracting portion of the nozzle 13, and further decelerating the vapor to a low

velocity in the expanding portion of the nozzle 13 and in the condensing chamber above this nozzle. Since the pressure drop within the rectifier varies from about $2\frac{1}{2}$ atmospheres at the cathode to substantially zero in the region of least pressure, it is possible by this process both to secure within the condensing chamber above the nozzle 13 a pressure high enough to greatly facilitate

10 cooling of the rectifier and to maintain a comparatively low pressure at the anodes 3 which are located in a region which is remote from the path of the vapor discharged from the cathode and is maintained at a pressure cor-

15 responding to that of the vapor when it is between the nozzles 12 and 13.

The embodiment of the invention illustrated and described herein has been selected for the purpose of clearly setting forth the principles involved. It will be apparent, however, that the invention is susceptible of being modified to meet the different conditions encountered in its use and I, therefore, aim to cover by the appended claims all modifications within the true spirit and scope of my invention.

What I claim as new and desire to secure by Letters Patent of the United States is:

1. A vapor electric device including an evacuated vessel, a vaporizable cathode located within said vessel, a condensing chamber above said cathode within said evacuated vessel, an anode chamber within said evacuated vessel, a contracting and expanding nozzle interposed between said cathode and said chamber to raise the vapor pressure in said condensing chamber and to lower the vapor pressure in said anode chamber, and means for circulating a cooling medium in contact with the surfaces of said condensing chamber, said nozzle, and said evacuated vessel.

2. A device including an insulation receptacle, a vaporizable cathode located within said receptacle, an evacuated vessel surrounding said receptacle and including an internal flange integral with said vessel and extending within said receptacle and downwardly below the upper edge of said receptacle, a condensing chamber within said evacuated vessel, and a contracting nozzle interposed between said cathode and said chamber.

3. A device including an insulation receptacle, a vaporizable cathode located within said receptacle, an evacuated vessel surrounding said receptacle and including an internal flange which overlaps the edge of said receptacle, a condensing chamber within said evacuated vessel, a contracting and expanding nozzle interposed between said cathode and said chamber, and means for circulating a cooling fluid in contact with the surfaces of said chamber, said nozzle, and said evacuated vessel.

4. A device including an evacuated vessel, a vaporizable cathode, and a receptacle arranged to insulate said cathode from said vessel, said vessel being provided with a flange integral with said vessel and arranged to extend within said receptacle and downwardly below the upper edge of said receptacle, said flange forming an expanding nozzle.

5. A vapor electric device including a vaporizable cathode, a condensing chamber, a plurality of nozzles interposed between said cathode and said chamber and spaced from one another to form an opening therebetween, the lower one of said nozzles being an expanding nozzle, the lower portion of the upper one of said nozzles being a contracting nozzle and the upper portion being an expanding nozzle, and an anode chamber interconnected with said opening, said lower one of said nozzles being tapered for a substantial distance above said cathode to expand the vapor therefrom to a relatively high velocity and relatively low pressure in the region of said opening between said nozzles, said lower portion of said upper one of said nozzles being tapered for a substantial distance above said opening to decelerate said vapor to a relatively low velocity in said expanding upper portion of said upper nozzle and in said condensing chamber, whereby a relatively high vapor pressure is maintained in said condensing chamber and a relatively low vapor pressure is maintained in said anode chamber.

6. A vapor electric device including a vaporizable cathode, a chamber arranged to condense the vapors emanating from said cathode, an anode chamber, and a plurality of nozzles arranged to form an opening between said cathode and said anode chamber, the lower one of said nozzles being an expanding nozzle, the lower portion of the upper one of said nozzles being a contracting nozzle and the upper portion of said upper one of said nozzles being an expanding nozzle, said lower one of said nozzles being tapered for a substantial distance above said cathode to expand the vapor therefrom to a relatively high velocity and relatively low pressure in the region of said opening, said lower portion of said upper one of said nozzles being tapered for a substantial distance above said opening to decelerate said vapor to a relatively low velocity in said expanding upper portion of said upper nozzle and in said condensing chamber, whereby a relatively high vapor pressure is maintained in said condensing chamber and a relatively low vapor pressure is maintained in said anode chamber.

7. A vapor electric device including a vaporizable cathode, a condensing chamber, an anode chamber, and two nozzles interposed in series between said cathode and said condensing chamber and forming an opening

therebetween, the lower one of said nozzles being an expanding nozzle arranged to conduct all of the vapor rising from said cathode, the lower portion of the upper one of said nozzles being a contracting nozzle and the upper portion of the upper one of said nozzles being an expanding nozzle, said lower one of said nozzles being tapered for a substantial distance above said cathode to expand the vapor therefrom to a relatively high velocity and relatively low pressure in the region of said opening, said lower portion of said upper one of said nozzles being tapered for a substantial distance above said opening to decelerate said vapor to a relatively low velocity in said expanding upper portion of said upper nozzle and in said condensing chamber, whereby relatively high vapor pressure is maintained in said condensing chamber and relatively low vapor pressure is maintained in said anode chamber.

In witness whereof, I have hereunto set my hand this 14th day of February, 1927.

DAVID C. PRINCE.
